APPARATUS FOR ELEVATING CONCRETE FORMS

Roy I. Patterson and Herman W. Foss, Minneapolis, Minn., assignors to Minot Builders Supply Co., Inc., a corporation of Minnesota

Continuation of application Serial No. 87,632, April 15, 1949. This application November 13, 1952, Serial No. 320,228

9 Claims. (Cl. 254—106)

1

Our invention relates to apparatus used in conjunction with the construction of concrete building walls. In general the invention relates to means for automatically elevating form sections used in constructing concrete walls and in particular it relates to a jack or normally a plurality of jacks automatically actuated by fluid pressure means to progressively elevate form sections and a concrete pouring platform by small consecutive increments of distance as the wall is poured.

This application is a continuation of our application Serial No. 87,632, filed April 15, 1949, now abandoned.

In pouring the concrete for large structures, such for example as concrete elevator bins or systems of concrete elevator bins, it has been customary to provide form sections conforming to the wall to be built, and these forms are connected with a platform upon which the concrete is received and moved to be poured into the upper open end of the forms. An extremely difficult problem has been encountered, especially with large concrete structures, in raising one or a large number of relatively heavy form sections and the platform or flooring connected therewith, which may cover the entire area of the structure being built. The forms, usually around four feet deep, must be raised very slowly so that the concrete at the bottom of the form will have had time to sufficiently set before the supporting forms are drawn up and away from the formed concrete. Further, the forms should in general be raised at a substantially uniform speed about the entire circumference or extent of the walls and partitions being built.

One method of raising these forms which has been followed is to have vertical rods embedded in the concrete, and to clamp to these rods hand-operated jacks which act to slowly lift the forms and the attached flooring; but this method involves a large number of workmen, is slow and uncertain in operation and frequently produces troubles which delay the pouring operation.

Another method disclosed in the prior art provides a mechanical jack wherein two sets of gripping dogs adapted to engage a jack rod are disposed on opposite sides of the working surface of the lifting frame. This method has been unsatisfactory because the lifting frames which are frequently made of wood are subject to warping and distortion. Also it frequently occurs that all of the jacks do not provide the same degree of movement, which results in tilting of the flooring which in turn causes tilting of the lifting frames to render the jacks inoperative. This is

2

particularly true when the sets of the gripping dogs are carried by members which are secured to the lifting frame.

We have discovered a more effective and more simple method of lifting the forms and the attached flooring than any yet disclosed in the prior art, whereby the jack surrounds a jack rod, but is independent of the lifting frame and therefore cannot be affected by warping or tilting of the lifting frame. The present jack has an upper and a lower member encompassing the jack rod and forming an annular pneumatically expandable chamber. Both the upper and lower members are connected to rod engaging bits which are supported by their respective members beneath the upper limits of the upper member and with their respective members form an integrated unit which lies entirely below the lower limits of the working surface of the lifting frame. Having our jack formed in such an integrated unit not only provides a cheaper and more simple device but due to the fact that it lies entirely below the working surface of the lifting frame it may act on said lifting frame without being connected thereto and, therefore, will be independent of any tilting effect which has made prior automatic means for lifting concrete forms ineffective.

We further discovered that a number of these pneumatic devices may be applied to concrete form sections throughout the circumference or total extent of the outer and partition walls, and that all of such devices may be caused to operate simultaneously by supplying high pressure compressed air to the expandable chamber of each of said devices, whereby the entire form structure and the attached flooring will be raised simultaneously by very small increments throughout the whole area of walls being built.

An object of our invention is to provide in combination with a lifting frame united with concrete form section and an adjacent flooring, and a jack rod embedded in the concrete between the opposite sides of the form, an improved lifting jack formed in an integrated unit and operative on the jack rod beneath the lower limits of the work surface of the lifting frame.

Another object is to provide a lifting jack which is independent of the lifting frame and is composed of a pair of movable members which encompass a jack rod beneath a working surface of the lifting frame, one of said members forming the lifting member and the other a follow up member to support the load on the rod during the movement of the lifting member, said members being resiliently connected to each other,

and both of said members having rod engaging bits connected thereto beneath the lower limits of the work surface of the lifting frame.

A further object is to provide a lifting jack formed of a pair of members which surround a jack rod and between them form an expandable chamber which is intermittently expanded to elevate a lifting frame, together with sets of rod engaging bits connected to each of the members for engaging the jack rod beneath the upper limits of the upper member, and an adjustable resilient follow-up connection between the members for adjusting the extent of lifting action, said members and their respective sets of bits forming an integrated unit beneath the working surface of the lifting frame on which the jack operates.

Other and further objects may be disclosed in the course of the following specification and claims, reference being had to the accompanying drawings wherein:

Fig. 1 is a top plan view of a somewhat complicated series of walls such as might result from building a small concrete country elevator, showing the distribution of lifting devices and the floor and the upper edges of the concrete forms in relation to the numerous lifting devices employed.

Fig. 2 illustrates a side elevation part schematic side view of an air tank, a valve for controlling compressed air therefrom and means for automatically opening and closing said valve.

Fig. 3 is a side elevation part sectional view of one of the units taken on an enlarged scale.

Fig. 4 is a fragmentary side elevation sectional view of a modified form of pneumatic air chamber.

Fig. 5 is a sectional plan view taken on line 5-5 of Fig. 3 but on a reduced scale.

Fig. 6 is a sectional plan view taken on line 6-6 of Fig. 3 but on a reduced scale.

Fig. 7 is a sectional plan view taken on line 7-7 of Fig. 3 with some parts broken away.

Fig. 8 is a side elevation view taken across one form section and a part of the floor connected therewith of the framework for carrying the lifting device with some parts in section.

A framework, shown in Fig. 8, for each of the lifting devices employed, comprises a lifting frame designated generally by the numeral 9. This lifting frame has vertical side members 10 and 11, which may be suitable studding or timbers. To the members 10 and 11 are secured by suitable means an upper set of cross pieces 12 and 13, see Fig. 1, and corresponding sets of lower cross pieces designated at 14, it being understood that there is a second lower cross piece, not shown, parallel to upper cross piece 13, Fig. 1. A working surface 15, Figs. 8 and 3, is formed on the lower side of the cross pieces 12 and 13. As shown in Fig. 1, there is a space 16 between the members 12, 13, 10 and 11 of the lifting frame 9. Through this space extends a jack rod 17, Fig. 8, preferably formed of steel, which extends vertically within and is anchored to the concrete wall 18, as indicated at 19, and which extends indefinitely upward as indicated at 20 in Fig. 8. This jack rod 17 is centered in both directions within the space 16 in the lifting frame 9.

As shown on a small proportionate scale in Fig. 8, the general reference numeral 21 represents a pneumatic jack formed in an integrated unit and adapted to act upon the working surface 15 of the lifting member 9. Jack 21 is com-

prised of a first member 22 and a second member 23. Connected to the first member 22 are rod engaging bits 24 and connected to member 23 are similar bits 25.

Referring now to Fig. 3, where the construction of jack 21 is shown in detail, the first member 22 of the jack 21 is formed with a top plate 26. The working surface 15 merely rests upon and the lifting frame 9 is supported upon plate 26. This important feature of the present invention makes the jack 21 effective against any tilting or stress of the lifting frame 9. Plate 26 has a central depending boss 27. An opening 28 in boss 27 is of a size to fit about the vertical rod 17 and act as a guide to hold the plate 26 in proper alignment with the rod 17. The top plate 26 is secured to a lower plate 29 by means of a series of bolts 30, which are shown in elevation in Fig. 3 and in transverse section in Figs. 6 and 7. The bolts 30 hold the top plate 26 and the plate 29 in fixed spaced relation by means of elongated tubular spacer members 31, which extend between the lower surfaces of out-standing ears 32 on plate 26 and the upper surfaces of similar ears 33 extending outwardly from plate 29. This arrangement permits plate 29 to act as a guide to hold plate 26 in proper alignment with rod 17. The plate 26, Fig. 3, has formed integrally therewith or rigidly attached thereto a depending annular flange 34 which forms a drum-like member 35 which is open at the bottom and which extends within the circle of bolts 30 and spacers 31, as clearly shown in Fig. 6.

The second member 23 which consists of a plate 36, is held to the plate 26 for movement in relation thereto by means of bolts 37 which extend through ears 38 formed in the periphery of plate 36, see Fig. 6, and through similar ears 39 on top plate 26. As clearly shown in Fig. 3, the bolts 37 are extended some considerable distance above the upper surface of plate 26 and each has on its top a nut 40 formed with a contact surface or attached washer 41. A tubular spacer 42 surrounds each bolt 37 between plate 26 and washer 41. Fairly strong compression springs 44 extend between the upper surface of each of the ears 39 and the lower surface of each washer 41 and normally hold washer 41 spaced a short distance above the upper end of spacer 42, as indicated at 45 in Fig. 3. This space makes possible a relative movement between the upper plate 26 and the lower plate 36 while one or the other of said members is held in a stationary position, and the distance is made adjustable by means of nuts 40.

The plate 36 is circular and is provided with a central circular opening 46 which fits slidably about the outer surface of the tubular boss 27, as shown in Fig. 3. The outer circular edge 47 of plate 36 is of such dimension that it fits slidably against the inner surface of the drum-like member 35 to form an annular chamber 48. An annular depending flange 49 is formed on the underside of plate 36 and is integrally connected with an annular horizontal flange 50 which extends outwardly into the ears 38. There is thus formed a right angle abutment at 51 between the plate 36 and the depending annular flange 49, as well as an annular extension 50 for supporting the ears 38, so that the bolts 37 may come outside of the outer surface of the annular drum-like member 35, see Fig. 6.

Within the annular chamber 48 inside of drum 35 and outside of the tubular boss 27 is positioned an expandible annular pneumatic tube member

52. This tube will normally be flattened at its sides, but it has contact with the sides of top plate 26 and bottom plate 36, as shown in Fig. 3. When compressed air, from a suitable source hereinafter outlined, is admitted to the space within the pneumatic member 52 from air tube 53 through connecting nipple 54 and inlet opening 55, Fig. 3, it is clear that the force exerted by the compressed air will tend to separate top plate 26 and plate 36 to expand the chamber 48. If the plate 36 is anchored to the rod 17 while this force is exerted, plate 26 and all the parts connected with it which form the first member 22, will be raised a short distance determined by the extent of the space 45, which is adjustable by operation of nut 40. This adjustment may vary from one-quarter of an inch to one-half an inch, depending upon the concrete setting condition of the weather at the time. It follows that when the first member 22 is raised, which contacts directly the working surface 15 of the lifting frame 9, see Fig. 8, the lifting frame 9 and all parts connected therewith, including the form sections and the floor, will be correspondingly lifted.

A variant form of pneumatic chamber is shown in Fig. 4. In place of the pneumatic tube 52, an annular rubber bottom liner 56 is set upon the upper surface of the plate 36. This is provided with an annular inner flap 57 which fits closely the outside of the depending tubular boss 27, and a similar annular outer flap 58 about the outer circumference of the liner 56 fits closely the inner surface of drum 35. The pressure of the air admitted to chamber 48 in this form will cause the annular flaps 57 and 58 to be pressed firmly against the respective outer surface of tubular boss 27 and the inner surface of the cylindrical drum 35 as the plate 26 and attached parts are moved upwardly. This will seal the chamber 48 against loss of air pressure and will permit the upper plate 26 to be lifted.

The sets of rod engaging bits indicated generally in Fig. 8 as 24 and 25 which support the members 22 and 23 for movement relative to each other will now be described in detail.

As shown in Fig. 3, secured to plate 36 are a number of bolt members 59 which are threaded at 60 into the plate 36. In the preferred arrangement of my invention there will be four of these members 59 each so connected with the plate 36 that they will be ninety degrees apart all the way around the jack rod 17. Each of these bolt members is identical with the others except as to position. The bolt members 59 are rigidly held in angular relation to the rod 17 and extend through an opening 61 in individual rod engaging bit 62. The bolt members 59 are threaded at 63 to receive thereon a nut 64. On the inner side of nut 64 is a coiled compression spring 65 which engages the center portion of bit 62. Each of the rod engaging bits 62 has a semi-spherical end 66 which fits into the angle abutment 51 heretofore described. Opposite the semi-spherical end 66 of each of the bits 62 is a sharpened end 67 which is curved as indicated in Fig. 5. Nut 64 is adjustable so that the spring 65 may always hold the bit 62 in firm gripping engagement with the rod 17.

A similar arrangement of rod engaging bits are connected to plate 29 which forms a part of the first member 22, as seen in Fig. 8. Here each of the bolt members designated at 68 has a threaded end 69 which is threaded into the plate 29. Likewise, there are preferably four of said bolts

each carried angularly disposed toward the rod 17, as shown in Fig. 3. Bolt members 68 extend through opening 69a in the rod engaging bits here designated at 70. The bolt members 68 are threaded at 71 to receive a nut 72 which compresses spring 73 against the rod engaging bits 70. Similarly the rod engaging bits 70 have rear curved ends 74, which engage angle abutments 75 between the lower side of plate 29 and depending flange members 76. Bits 70 have sharpened inner ends 77. The second set of four rod engaging bits and their relation to rod 17 is shown in Fig. 5. This arrangement is shown for the lower set of rod engaging bits, as indicated by line 5-5, but it is identical with the arrangement of the upper set of rod engaging bits 62. As shown, the curved end 77 of bits 70 engages an arc of the circumference of rod 17.

Referring now to Figs. 1 and 8, the building construction used in conjunction with the lifting frames 9, and the lifting jacks 21, will be explained. Referring first to Fig. 8, the wall forms are composed of a pair of members 78, 79, which as shown in Fig. 1, may be arcuate or of any particular configuration as is needed to form the walls of the desired building. Members 78, 79 are secured to the opposing legs 10 and 11 of the lifting frame 9 by a plurality of supporting members designated at 80 and 81. A floor surface 82 is secured to one of the wall forms. Referring now to Fig. 1, is shown the manner in which the wall forms 78, 79 and the flooring 82 are arranged for the building of a grain elevator. The elevator construction here shown is composed of a first bin 83, a second bin 84, with a plurality of smaller chambers designated at 85, 86, 87, 88, 89, 90 and 91, being situated between the two large bins 83 and 84. It will be noted that a multiplicity of lifting frames 9 connect the wall forms so as to simultaneously raise all portions of the wall form as the building walls are constructed.

Referring now to Fig. 2, is shown the mechanism for energizing the lifting jacks 21, consisting of an intermittently operable pneumatic system. On a platform 92, which in Fig. 1 is shown mounted in chamber 86, is a tank 93 adapted to contain air under pressure, supplied from a source not shown. An outlet conduit 94 carrying a gauge 95 and a control valve 96 permits air to pass through a conduit 97 to a mechanically operated timing valve 98 having an outlet conduit 99. A valve plunger 100 which controls the passage of air through the valve 98 extends through the upper side of the timing valve 98 and is controllably moved by a beam 101 supported on a bearing 102, and rotatably rocked by a motor driven cam 103, which rotates counter-clockwise as shown by the arrow. The conduit 99, as seen in Fig. 8, extends to all of the multiplicity of jacks 21 and is with respect to each jack connected to the jack through the tube 53, shown in Fig. 3. A release valve 104 permits escape of air from the timing valve 98.

The operation of the lifting jacks will now be explained. Assuming that a structure such as is designated in Fig. 1 has been started, and that air under pressure is present in tank 93, and that the cam 103 is periodically rocking the beam 101 to actuate the timing valve 98 to periodically permit air under pressure to pass through conduit 99 and through the individual conduits 53 to the chamber 48 of the jack shown in either Fig. 3 or Fig. 4. When compressed air is introduced into the pneumatic member 47, of Fig. 3,

or into the chamber 48, of Fig. 4, above the diaphragm 54, it will apply opposing force between the top plate 26 and the bottom plate 36, thereby tending to push these plates apart. Since plate 36 is held against movement in a downward direction by the multiplicity of bits 62, the upper plate 26 and all parts associated therewith will move upwardly raising the lifting frame 9, including the flooring on which the work is being performed. The extent of movement is limited by the space 45 between members 42 and members 41. During this movement the lower set of bits designated generally at 24 and consisting of bit members 70 will slidably move upwardly on the jack rod 11, while the upper set of bits 25 and consisting of individual bits 62 will bite into the jack rod 11 and support the structure on the jack rod during the elevating movement. Assuming now that the forms and flooring have been raised to their maximum limit, cam 103 will have completed a circular movement, and air in the several chambers 48 of the multiplicity of jacks will then be released through the release valve 104 of the timing device 98, thereby diminishing the pressure within the chambers 48. When this occurs, the multiplicity of springs 44 which have been under compression, will expand to move the lower plates 35 upwardly. This second action causes the weight of the structure to be borne by the lower set of bits 24, since the upper set of bits 25 will move simultaneously with the plate 36. During the process of periodically raising the forms, the multiplicity of jacks, even though connected to a common source of pressure in tank 93, may not all move the same distance, and this will likely cause a tilting of the floor 82 and some of the forms 9 with respect to their wall structure. Individual adjustment of jacks may take place through valve means not shown, but connected between conduit 99 and each of the individual conduits 53 to the respective jacks. However, any tilting of the lifting form will have no effect on the operation of a particular jack, since each jack is situated beneath the working surface 15 of its respective frame, and therefore will not be influenced by the tilting of the frame. It should be understood that any tilting of any frame would only be a relatively small amount, but this has been a difficult problem to overcome and has been the source of a great deal of difficulty in using these automatic jacks.

The advantages of our invention reside in the use of automatic jacks, which may be coupled into a parallel pneumatic system to automatically raise a building form during the construction of the walls thereof.

A particular advantage resides in providing jacks which are independent of the lifting frames and are formed as integrated units to be situated beneath the working surface of lifting frames to automatically raise the frames at a predetermined rate as the concrete is poured between the frames.

As numerous changes might be apparent to those skilled in the art, our invention is not confined to the specific structure shown, but is defined in the terms of the appended claims.

We claim:

1. A jack for supporting and raising a lifting frame on a jack rod, comprising a first movable member encompassing the jack rod and formed to act on a lower portion of a work surface of the frame, a second movable member encompassing the jack rod beneath the first member, said

second member being spaced beneath the first member, means acting within the space between said members for intermittently moving said first member vertically on the jack rod and relative to the second member to raise the lifting frame, means connecting said members and forming a resilient follow up connection for moving the second member vertically on the jack rod in the direction of the first member between intermittent movements of the first member, a first set of rod engaging bits connected to said first member and having sliding engagement with the rod when said first member is moved, and a second set of rod engaging bits connected to the second member, both of said sets of bits supported by their respective members beneath the upper limits of the first member and with their respective members forming an integrated unit beneath the lower limits of the work surface of the lifting frame.

2. A jack for supporting and raising a lifting frame on a jack rod, comprising a first movable member encompassing the jack rod and formed to act on a lower portion of a work surface of the frame, a second movable member encompassing the jack rod beneath the first member, an intermittently operable driven member positioned between said first and second members and acting on the first member to move said first member vertically on the jack rod relative to the second member, means connecting said members and forming a resilient follow up connection for moving the second member vertically on the jack rod in the direction of the first member between intermittent movements of the first member, a first set of rod engaging bits connected to said first member and having sliding engagement with the rod when said first member is moved, and a second set of rod engaging bits connected to the second member, both of said sets of bits supported by their respective members beneath the upper limits of the first member and with their respective members forming an integrated unit beneath the lower limits of the work surface of the lifting frame.

3. A jack for supporting and raising a lifting frame on a jack rod, comprising a first movable member encompassing the jack rod and formed to act on a lower portion of a work surface of the frame, a second movable member encompassing the jack rod beneath the first member, a pressure operated device positioned between said members, intermittently operable pressurizing means connected to said pressure operated device and effective to raise the first movable member on the jack rod relative to the second movable member, means connecting said members and forming a resilient follow up connection for moving the second member vertically on the jack rod in the direction of the first member between intermittent movements of the first member, a first set of rod engaging bits connected to said first member and having sliding engagement with the rod when said first member is moved, and a second set of rod engaging bits connected to the second member, both of said sets of bits supported by their respective members beneath the upper limits of the first member and with their respective members forming an integrated unit beneath the lower limits of the work surface of the lifting frame.

4. A jack for supporting and raising a lifting frame on a jack rod, comprising a first movable member encompassing the jack rod and formed to act on the lower portion of a work surface of the lifting frame, a second movable member en-

compassing the jack rod beneath the first member, means acting between said members for intermittently moving the first member vertically on the jack rod and relative to the second member, means connecting said members and forming a resilient follow up connection for moving the second member vertically on the jack rod in the direction of the first member, guiding means rigidly united with the first member and embracing the jack rod beneath the second member for holding the first and second members in vertical alignment with the jack rod, a first set of rod engaging bits connected to said first member beneath its upper limits and having sliding engagement with the jack rod when said first member is moved, and a second set of rod engaging bits connected to the second member, both of said sets of bits supported by their respective members beneath the upper limits of the first member and with their respective members forming an integrated unit beneath the work surface of the lifting frame.

5. A jack for supporting and raising a lifting frame on a jack rod, comprising a first movable member encompassing the jack rod and formed to act on a lower portion of a work surface of the frame, said member having a depending peripheral flange forming a chamber on the lower surface of said member, a second movable member encompassing the jack rod and positioned within the peripheral flange of the first member to form a lower surface of said chamber, means for intermittently introducing a pressure fluid into said chamber for moving said first member relative to the other member, a plurality of guide rods extending between the peripheral limits of said first and second members, a spring surrounding each of said rods and engaging one of said members and with the respective guide rod forming a follow up connection between said members for moving the second member in the direction of the first member between intermittent movements of the first member, a first set of rod engaging bits depending angularly from said first member and engaging the jack rod, and a second set of rod engaging bits depending angularly from the second member and engaging the jack rod, both of said sets of bits supported by their respective members beneath the upper limits of the first member and with their respective members forming an integrated unit beneath the lower limits of the work surface of the lifting frame.

6. A jack for supporting and raising a lifting frame on a jack rod, comprising a first movable member encompassing the jack rod and formed to act on a lower portion of a work surface of the frame, said member having a depending peripheral flange forming a chamber on the lower surface of said member, a second movable member encompassing the jack rod and positioned within the peripheral flange of the first member to form a lower surface of said chamber, means for intermittently introducing a pressure fluid into said chamber for moving said first member relative to the second member, a plurality of guide rods extending between the peripheral limits of said first and second members, a spring surrounding each of said rods and engaging one of said members and with the respective guide rod forming a follow up connection between said members for moving the second member in the direction of the first member between intermittent movements of the first member, limiting means cooperable with each of said

5 spring means for limiting the extent of movement of the first member relative to the second member, a first set of rod engaging bits connected to said first member beneath its upper limits and having sliding engagement with the rod when the first member is moved, and a second set of rod engaging bits connected to the second member, both of said sets of bits supported by their respective members beneath the upper limits of the first member and with their respective members forming an integrated unit beneath the work surface of the lifting frame.

7. A jack for supporting and raising a lifting frame on a jack rod, comprising a first movable plate encompassing the jack rod and formed to act on a lower portion of a lifting frame, said plate having a depending peripheral flange forming a chamber on the lower surface of said plate, a second movable plate encompassing the jack rod beneath the first plate and positioned within the peripheral flange of the first plate to form a lower surface of said chamber, air sealing means within the chamber and independent of each of said plates, bolts extending between the outer portions of each of said plates, a coil spring surrounding each of said bolts and normally moving said plates to maximum separated position, an annular abutment formed on the bottom plate, a plurality of bolts secured to the bottom plate and extending angularly therefrom, a plurality of clamping bits each having an opening through which the bits are loosely held by said bolts, said bits being otherwise unconnected with any member with a sharpened end edge engageable with the jack rod and with its other end engageable with said abutment, and a spring surrounding the bolt and forcing the sharpened edge of the bit against the jack rod.

8. A jack for supporting and raising a lifting frame on a jack rod, comprising a first movable plate encompassing the jack rod and formed to act on a lower portion of a lifting frame, said plate having a depending peripheral flange forming a chamber on the lower surface of said plate, a second movable plate encompassing the jack rod beneath the first plate and positioned within the peripheral flange of the first plate to form a lower surface of said chamber, the top plate formed with a boss surrounding the jack rod, air sealing means independent of the plates within said chamber, a plurality of bolts extending through the outer portions of said plates, coil springs surrounding said bolts and normally holding the plates in maximum separated position, a third plate surrounding the jack rod below the second plate and connected to the top plate, an abutment formed on the lower surface of the bottom chamber plate and the third plate, sets of bolts secured to the bottom chamber plate and the third plate, sets of clamping bits each having an opening through which the bits are held by said bolts, said bits being otherwise unconnected with any member, but having sharp end edges engageable with the jack rod and having their other ends engaging the respective abutments, and a coil spring surrounding each bolt and engaging the respective bit for holding the sharpened end of the bit against the jack rod.

9. A jack for supporting and raising a lifting frame on a jack rod, comprising a first movable plate encompassing the jack rod and formed to act on a lower portion of a lifting frame, said plate having a depending peripheral flange forming a chamber on the lower surface of said

11

plate, a second movable plate encompassing the jack rod beneath the first plate and positioned within the peripheral flange of the first plate to form a lower surface of said chamber, one of said plates formed with a boss surrounding the jack rod, air sealing means independent of the plates within the chamber, bolts extending through outer portions of both plates, coil springs surrounding said bolts and normally moving the plates a maximum separated position, a third plate below and spaced from the bottom plate and connected with the top plate, abutments formed on the undersides of the bottom plate and the third plate, sets of clamping bits extending angularly between said abutments and the jack rod, said bits having sharp end edges

10

15

12

engageable with the rod and having their other ends engaging the respective abutments, and springs engageable with the bits for forcing the sharp end edges of the bits against the jack rod.
